REFRIGERATION

Nils Erland af Kleen, Stockholm, Sweden, assignor to Kleen Refrigerator, Inc., Hoboken, N. J., a corporation of Delaware

Original application October 3, 1941, Serial No. 413,441. Divided and this application April 24, 1943, Serial No. 484,377

7 Claims. (Cl. 62—99)

This invention relates to new and useful improvements in refrigeration and is directed more particularly to an evaporator construction formed with a plurality of cooling parts having alternate cooling and inactive periods, the present application being a division of my co-pending application, Ser. No. 413,441, filed October 3, 1941.

One of the primary objects of the present invention is to improve the efficiency of an evaporator construction of the type above mentioned by providing a number of air channels or spaces in the evaporator each of said air spaces being formed between a separate pair of cooling parts, each of the cooling parts of each pair producing refrigeration intermittently but in out of phase relationship with respect to one another and with the cooling parts of one of said pairs each being thermally connected to a separate one of the cooling parts of a separate one of the other parts.

With the above and other objects in view which will appear as the description proceeds, my invention resides in the novel features hereinafter more fully set forth, illustrated by way of example in the accompanying drawings and more particularly pointed out in the appended claims.

Referring to the drawings in which numerals of like character designate similar parts throughout the several views—

Fig. 1 is a diagrammatic view of refrigerating apparatus including an evaporator construction shown in front elevation having a plurality of cooling parts and with such cooling parts arranged in accordance with the present invention;

Fig. 2 is a top plan view of the evaporator construction of Fig. 1;

Fig. 3 is a view in elevation looking from the back of the evaporator construction, and

Fig. 4 is a diagrammatic view of the two groups of coils forming the cooling parts of the evaporator construction.

In the drawings, referring more particularly to Fig. 1, a refrigerator cabinet 10 is shown partly broken away and in section to illustrate the thermally insulated storage space 11 in which is arranged my improved evaporator construction including a pair of ice-freezing or sharp freezing compartments 12 and 13 and a plurality of vertical cooling coils divided into two groups. One group comprises cooling coils 14, 15, 16 and 17 connected at one end to the bottom of a down pipe 18 leading from the bottom of a thermally insulated vessel 19 disposed in the upper portion of the cabinet 10, and the other group including coils 14a, 15a, 16a and 17a similarly connected to the bottom of a down pipe 18a leading from the

bottom of another thermally insulated vessel 19a adjacent the first-mentioned vessel 19. The other end of each coil in each group terminates in communication with the associated vessel adjacent the upper portion of the latter.

5 The compartments 12 and 13 are arranged side by side in spaced relation to one another to provide an air space or channel 20 therebetween and each compartment has a separate pair of cooling coils thermally bonded to its heat conducting walls.

In the arrangement shown, coils 14 and 14a are employed for the compartment 12 and are arranged respectively on the left and right sides thereof, and coils 15 and 15a are employed

15 for the compartment 13 and are arranged respectively on the left and right sides thereof. Thus each compartment has a separate pair of cooling coils arranged to produce refrigeration in direct thermal transfer relation thereto, each pair comprising a cooling coil of one group and a cooling coil of the other group.

20 Moreover, as the air space or channel 20 is formed between coils 14a and 15, the air in said channel will be cooled by a coil of one group and a coil of the other group. Cooling coil 16a of one group is arranged in spaced relation to cooling coil 14 of the other group to provide a vertical air channel 21 along the left side of compartment 12 for circulating air in the storage space 10. Similarly, cooling

25 coil 16 of the other group is arranged in spaced relation to cooling coil 16a of the first group to provide a similar air channel 22 along the right side of compartment 13. Consequently, each of

30 the air channels 21 and 22 is formed between a cooling coil of one group and a cooling coil of the other group producing refrigeration in indirect thermal transfer relationship with respect to one another but with one of the cooling coils of each channel also producing refrigeration in direct

35 thermal transfer relation to the associated one of the compartments 12 and 13.

35 In order to present relatively large heat transferring surfaces for the air flowing in contact therewith, each of the cooling coils 16 and 16a

40 may have welded or otherwise suitably secured thereto a vertical plate 23 and 23a, respectively, preferably provided with laterally extending fins 24 and 24a, respectively, that project inwardly into the respective channel as clearly shown in

45 Figs. 1 to 3.

Adjacent the rear of the compartments 12 and 13 and in indirect thermal transfer relation thereto, the cooling coil 17 of one group and the corresponding cooling coil 17a of the other group

50 are arranged in indirect thermal transfer rela-

tion to each other to provide an air channel 25 (Fig. 2), each of said coils being provided with a vertical plate 26 and 26a, respectively, formed with laterally extending fins 27 and 27a, respectively, to present relatively large heat transferring surfaces for the air circulating in the channel 25. Thus, each of the channels 20, 21, 22 and 25 is formed between a pair of cooling coils, each pair comprising a cooling coil of one group and a cooling coil of the other group.

The vessels 19 and 19a are supplied with refrigerant liquid alternately from any suitable source or sources for operation of the respective groups of cooling coils on alternate cooling and inactive periods and in out of phase relation to one another for the provision of substantially continuous refrigeration.

In Fig. 1 I have shown for illustrative purposes vessel 19 and associated group of cooling coils 14, 15, 16 and 17 as forming parts of an intermittent type absorption refrigerating system A having alternate generation and absorbing periods and including the usual boiler-absorber 28 and condenser 29, and vessel 19a and associated group of cooling coils 14a, 15a, 16a and 17a as forming parts of a similar refrigerating system B including boiler-absorber 28a and condenser 29a, said systems operating in out of phase relation to each other so that when one system is generating and refrigerant liquid is delivered to its associated vessel and group of cooling coils, the other system is absorbing and refrigerant liquid is evaporated in its associated group of cooling coils to produce refrigeration. The heat necessary to liberate the refrigerant from the absorbent during the generating periods of each of the systems A and B is supplied by any suitable means such as the burners 30 and 30a, respectively.

It will thus be seen from the foregoing construction of the evaporator and arrangement of the different cooling coils that each of the compartments 12 and 13 will be directly cooled by a separate pair of cooling coils each pair comprising a cooling coil of one group and a cooling coil of the other group producing refrigeration intermittently but in out of phase relation to one another and arranged in thermal contact with the heat conducting walls of the respective compartment on opposite sides of the latter so that each compartment and associated pair of cooling coils form a separate low temperature cooling unit suitable for ice-freezing or for maintaining sharp freezing conditions. Moreover, each of said compartments will also be indirectly cooled along the sides and back thereof through the medium of air in separate channels, each channel formed between a separate pair of cooling coils, each pair comprising a cooling coil of one group and a cooling coil of the other group arranged in spaced parallel relation and producing refrigeration intermittently but in out of phase relation to one another.

In one of the air channels, namely, channel 20, the air is cooled by a pair of coils each of which is arranged in thermal contact with a respective low temperature compartment, in another one or more of the air channels, namely, channels 21 and 22, the air in each channel is cooled by a separate pair of coils one of which coils in each pair is arranged in thermal contact with a respective low temperature compartment and the other of which coils in each pair is arranged out of thermal contact with respect to either of the low temperature compartments, and in still another one of the air channels, namely, channel

25, the air is cooled by a pair of coils each of which is arranged out of thermal contact with respect to either of the low temperature compartments.

It will also be observed that as certain cooling coils of each of the two groups, namely, cooling coils 16 and 17 of one group and corresponding cooling coils 16a and 17a of the other group, are arranged out of thermal contact with respect to one another and to the freezing coils 14, 14a, 15 and 15a, and are employed to cool the air in the main storage space of the cabinet to maintain a temperature above freezing in the latter, each of said air cooling coils will become coated with frost during its refrigeration producing periods and will become automatically defrosted during its inactive periods so that a relatively high humidity will be maintained in said storage space.

From the foregoing it is believed that the construction and advantages of my invention will be readily understood by those skilled in the art without further description, it being borne in mind that numerous changes may be made in the details disclosed without departing from the spirit of the invention as set forth in the following claims:

What I claim is:

1. A refrigerator comprising a cabinet having a plurality of compartments to be cooled including two arranged side by side and adapted to be cooled to relatively low temperatures and another one adapted to be cooled to a relatively high temperature; and refrigerating apparatus including a plurality of cooling elements having alternate cooling and inactive periods and arranged in pairs including one pair disposed between said two first named compartments with one of the cooling elements of said pair in thermal contact with one and the other one of the cooling elements of said pair in thermal contact with the other one of said compartments, a second pair disposed on another side of one of said two first named compartments with one of the cooling elements of said pair in thermal contact and the other one of the cooling elements out of thermal contact with said compartment to provide a cooling channel for the air in said relatively high temperature compartment, a third pair disposed on another side of the other one of said two first named compartments with one of the cooling elements of said pair in thermal contact and the other one of the cooling elements of said pair out of thermal contact with said compartment to provide another cooling channel for the air in said relatively high temperature compartment, and means for operating one of the cooling elements of each of said pairs as a group and the other one of the cooling elements of each of said pairs as another group.

2. A refrigerator as claimed in claim 1 including a fourth pair in which the cooling elements are arranged out of thermal contact with either of said relatively low temperature compartments and in spaced relationship to one another to provide another cooling channel for the air in said relatively high temperature compartment.

3. A refrigerator comprising, in combination, a cabinet having a pair of low temperature compartments arranged side by side and a thermally insulated storage space; and refrigerating apparatus for cooling said compartments and storage space including a plurality of evaporator parts having alternate cooling and inactive periods and arranged in pairs including one pair disposed between said low temperature compartments with

one of said evaporator parts thermally bonded to one of said compartments and the other one of said evaporator parts thermally bonded to the other one of said compartments, a second pair disposed on another side of one of said compartments with one of said evaporator parts thermally bonded to said compartment and the other one of said evaporator parts out of thermal contact with respect to said compartment and spaced outwardly therefrom to provide a cooling channel for the air in said storage space, a third pair disposed on another side of the other one of said compartments with one of said evaporator parts thermally bonded to said compartment and the other one of said evaporator parts out of thermal contact with respect to said compartment and spaced outwardly therefrom to provide another cooling channel for the air in said storage space, and means including a conduit connected to deliver refrigerant liquid intermittently to one of the evaporator parts of each of said pairs for operation as a group and another conduit connected to deliver refrigerant liquid intermittently to the other one of the evaporator parts of each of said pairs for operation as another group.

4. A refrigerator comprising, in combination, a cabinet having a pair of low temperature compartments arranged side by side and a thermally insulated storage space; and refrigerating apparatus for cooling said compartments and storage space including a plurality of evaporator parts arranged in pairs including one pair disposed between said low temperature compartments with one of said evaporator parts thermally bonded to one of said compartments and the other one of said evaporator parts thermally bonded to the other one of said compartments, a second pair disposed on another side of one of said compartments with one of said evaporator parts thermally bonded to said compartment and the other one of said evaporator parts out of thermal contact with respect to said compartment and spaced outwardly therefrom to provide a cooling channel for the air in said storage space, a third pair disposed on another side of the other one of said compartments with one of said evaporator parts thermally bonded to said compartment and the other one of said evaporator parts out of thermal contact with respect to said compartment and spaced outwardly therefrom to provide another cooling channel for the air in said storage space, and means including a thermally insulated vessel constructed and arranged alternately to supply refrigerant liquid to and withdraw refrigerant vapor from one of the evaporator parts of each of said pairs for operation as a group and another thermally insulated vessel constructed and arranged alternately to supply refrigerant liquid to and withdraw refrigerant vapor from the other one of the evaporator parts of each of said pairs for operation as another group.

5. A refrigerator comprising, in combination, a cabinet having a thermally insulated storage space and a plurality of compartments including two arranged side by side and in heat exchange relation with the air in said storage space; and refrigerating apparatus for cooling said compartments and storage space including a plurality of

evaporator parts arranged in pairs including one pair disposed between said two-named compartments with one of said evaporator parts thermally bonded to one of said compartments and the other one of said evaporator parts thermally bonded to the other one of said compartments, a second pair disposed on a side of one of said compartments opposite to said first pair and with one of said evaporator parts thermally bonded to said compartment and the other one of said evaporator parts out of thermal contact with respect to said compartment and spaced outwardly therefrom to provide a cooling channel for circulating air in said storage space, a third pair disposed on a side of the other one of said compartments opposite to said first pair and with one of said evaporator parts thermally bonded to said compartment and the other one of said evaporator parts out of thermal contact with respect to said compartment and spaced outwardly therefrom to provide another cooling channel for circulating air in said storage space, and means constructed and arranged to operate one of the evaporator parts of each of said pairs as a group on alternate cooling and inactive periods and the other one of the evaporator parts of each of said pairs as another group on alternate cooling and inactive periods.

6. A refrigerator comprising, in combination, a cabinet having a thermally insulated storage space and a pair of low temperature compartments arranged side by side in said storage space; and refrigerating apparatus for cooling said compartments and storage space comprising a pair of intermittent absorption refrigerating systems each having a plurality of evaporator parts, one of the evaporator parts of each of said systems being arranged between said low temperature compartments with the evaporator part of one of said systems thermally bonded to one of said compartments and the evaporator part of the other system thermally bonded to the other one of said compartments, another evaporator part of each of said systems being arranged on the opposite side of said first-named compartment with the evaporator part of said second system thermally bonded to said one compartment and the evaporator part of said first system out of thermal contact with respect to said one compartment and spaced outwardly therefrom to provide a cooling channel for the air in said storage space, and a third evaporator part of each of said systems being arranged on the opposite side of said second-named compartment with the evaporator part of said first system thermally bonded to said compartment and the evaporator part of said second-named system out of thermal contact with respect to said second-named compartment and spaced outwardly therefrom to provide another cooling channel for the air in said storage space.

7. A refrigerator as claimed in claim 6 including a fourth evaporator part of each of said systems arranged out of thermal contact with respect to either of said compartments to cool the air in said storage space.

NILS ERLAND AF KLEEN.
